JEWELRY

Andrew R. Coté, Brooklyn, N. Y.

Application September 3, 1938, Serial No. 228,303

5 Claims. (Cl. 63—20)

This invention relates to an improvement in the construction of certain types of jewelry employing pearls or other precious stones mounted upon a metallic foundation, and has for its principal object the improvement of the appearance of such an article by the concealment of said foundation.

An important object of my invention, is to provide means for making an attractive, inexpensive and durable cross of beads such as pearls and the like, in which the mounting thereof is concealed.

Other objects and advantages of my invention will either become apparent or be specifically referred to in the following description thereof wherein reference is made to the accompanying drawing, in which

Figure 1 illustrates the appearance of a cross of pearls constructed in accordance with my invention.

Figure 2 is an enlarged cross-sectional view taken on a line 2—2 of Figure 3 and looking in the direction of the arrows.

Figure 3 is an enlarged cross-sectional view taken on line 3—3 of Figure 2 looking in the direction of the arrows.

Figures 4 and 5 show different means of securing terminal pearls on the mounting therefor.

Figure 6 illustrates the appearance of a bar pin constructed according to my invention.

Figure 7 is an enlarged cross-sectional view of the pin shown in Figure 6.

Figure 8 is a view of the pin shown in Figure 7 as seen from the right-hand end thereof.

Referring now to Figures 2 and 3, it will be understood that a cross structure employing a preferred embodiment of my invention comprises a tube 10 forming a part of the upright portion of the cross. The tube 10 is provided with clearance holes drilled transversely therethrough at a point between the ends thereof, to receive a screw threaded rod 11. The cross-bar of the structure is formed by a plurality of tube sections 12, having cemented or otherwise suitably secured to one end thereof a terminal pearl or bead 13, which bead is first partially drilled through, on an axis thereof to receive said tubes. Screw threads 14, adapted to cooperate with the threaded rod 11 are formed in the tubes 12 proximate the ends thereof remote from the bead 13. Figure 4 is a view of what may be described as one form of terminal jewel or bead means comprising the tube and terminal bead assembly as above described.

A terminal bead 15, similar to beads 13, may be mounted on a tube 16, similar in all respects

to the tube 13. A threaded rod 17 similar to the rod 11 is screwed into threads tapped into the lower end of a tube 10, as shown, and serves, as does the rod 11, for securing the tube 16 and terminal bead 15 to the lower end of the upright portion of the cross to make a mounting structure of a proportion which will give to the same the appearance of a conventional ecclesiastical cross.

A center bead 20, having holes of a size suitable and adapted to slide freely on either the tube 10 or 12, are drilled on axes disposed in a common plane and intersecting each other at right angles. What might be described as spacer or intermediate beads 21, and an upper terminal bead 22, are provided with holes passing through the center thereof of such diameter that the beads are adapted to slide freely on any of the tubes 10, 12 or 16.

A mounting 23 of any suitable form having a threaded shank 24 screwed into the upper end of the tube 10 is adapted to secure the terminal bead 22 to the structure and for convenience the bead 22 and mounting 23 may be described as terminal jewel or bead means similar to the terminal members which include the beads 13 and 15.

The device above described may be assembled by first positioning the center bead 20 on the tube 10 after which the rod 11 is passed through both the bead and the clearance holes in the tube 10 provided, as above described, to receive the rod 11. Thereafter, a spacer bead 21 is disposed on a tube 12 adjacent the terminal bead 13 thereof and the tube then screwed on the end of the rod 11 until the same projects, as shown in Figure 2, into the center bead to a point in contact with or at least proximate the tube 10. The other side arm of the cross will of course be assembled in the same way. Similarly, the three spacer beads shown in Figure 2 below the center bead 20 may be held in position on either the tubes 10 or 16 as the case may be by the terminal bead means 15 and tube 16 to which the same is secured. The spacer bead 22 on the upper end of the tube 10 is held in position by the mounting 23 which passes through the terminal bead 22 as shown.

It will be understood that the length of the tubes 12 is preferably such that when they are secured tightly against the tube 10 the intermediate bead 21 will be held between the beads 13 and 20 against lateral movement and yet not be subjected to pressure sufficient to crack or injure any of said beads. Correspondingly, the length of the tubes 10 and 16 are such that the beads

forming the upright portion cannot be subjected to an injurious pressure.

Figure 5 illustrates a modified form of device shown in Figure 4 in that the inner end of the 5 hole 25 formed in the bead 13 is enlarged at 26 to receive the head of an angular screw 27 having a threaded shank 28. The screw 27 is of such size that it may be inserted into the bead with the head thereof in the position shown. 10 When the tube 12 is screwed onto the shank 28 of the screw 27 the shank is positioned centrally of the hole 25 with the result that the bead 13 is held firmly on the end of the tube 12.

Figures 7 and 8 show a bar pin structure in 15 which terminal beads 30 are mounted like those above described on tubes 31 and intermediate beads 32 and 33 are mounted on a tube 34 similar to the manner in which the beads 21 and 22 are mounted on the tube 10 above described. In the 20 case of the bar pin, however, while the beads 32 are drilled in two directions similar to that described in the case of the center bead 20, above, the hole 35, drilled at right angles to that through which the tube 34 extends, does not extend entirely through the head. A pin structure 36 having a threaded end 37 adapted to screw into suitably tapped holes in the tube 34 is mounted through the hole 35 in the left-hand bead 32 and similarly, a suitable clasp structure 38, having 25 a threaded end 39 is mounted on the tube 34 through the hole 35 in the right-hand bead 32.

It will be understood that the holes 35 in the beads 32 serve, in addition to making it possible to mount the pin and clasp structure 36-38 on 30 the tube 34, as sufficient clearance to enable the terminal beads 30 to be tightened sufficiently to hold all the intermediate beads against longitudinal movement and at the same time not subject them to a destructive pressure.

40 This invention is made to fill a need for improvements in jewelry. It is understood that various modifications in structure, as well as changes in mode of assembly and manner of use, may occur to those skilled in the art, especially 45 after benefitting from the teachings of my invention. Hence, it will be understood that this disclosure is merely illustrative of preferred means of embodying the invention in useful form and to explain the construction, operation and 50 advantages thereof.

What is claimed is:

1. A piece of jewelry having a rigid mounting and a plurality of intermediate bead-like jewels strung thereon, in combination with terminal 55 bead-like jewel means at each end of said mounting in alignment therewith for holding said intermediate jewels against longitudinal movement along said mounting, said jewel means comprising means engaging said mounting for securing the same at the end thereof.

2. A piece of jewelry having a rigid mounting and a plurality of intermediate bead-like jewels strung thereon, in combination with terminal bead-like jewel means at each end of said mounting in alignment therewith for holding said intermediate jewels against longitudinal movement along said mounting, said jewel means comprising means engaging said mounting for securing the same at the end thereof, and means connected to said mounting for supporting the piece 65 when used as an adornment.

3. A cross-shaped ornament comprising a center bead-like jewel having a pair of holes drilled therein on axes intersecting each other at right angles, a member passing through one of said holes and extending from opposite sides of said center jewel, a pair of other members each having one end thereof disposed in one end of the other hole in said center jewel and proximate said first mentioned member whereby said members project respectively, from opposite sides of said jewel, and means for rigidly securing to said first mentioned member the ends of said other members disposed proximate thereto, in combination with at least one intermediate bead-like jewel strung on each of said aforesaid members, and a plurality of terminal bead-like jewel means each mounted at the end of an aforesaid member and in alignment therewith for holding against longitudinal movement along said member an intermediate jewel, said jewel means comprising means engaging said member for securing the jewel means at the end thereof. 10

4. A cross-shaped ornament comprising a center bead-like jewel having a pair of holes drilled therein on axes intersecting each other at right angles, a member passing through one of said holes and extending from opposite sides of said center jewel, a pair of other members each having one end thereof disposed in one end of the other hole in said center jewel and proximate 15 said first mentioned member whereby said members project respectively, from opposite sides of said jewel, and means for rigidly securing to said first mentioned member the ends of said other members disposed proximate thereto, in combination with at least one intermediate bead-like jewel strung on each of said aforesaid members, and a plurality of terminal bead-like jewel means each mounted at the end of an aforesaid member and in alignment therewith for holding against longitudinal movement along said member an intermediate jewel, said jewel means comprising 20 means engaging said member for securing the jewel means at the end thereof. 25

5. A cross-shaped ornament when used as an ornament.

5. A cross-shaped ornament comprising a center bead having a pair of holes drilled therein on axes intersecting each other at right angles and lying in a common plane, a major tube member passing through one of said holes and extending from opposite sides of said center bead, a pair of minor tube members each having one end thereof disposed in said center bead proximate said first mentioned tube member and projecting respectively, from opposite sides of said center bead, and means for rigidly securing to said first mentioned member the ends of said other members disposed proximate thereto, in combination with at least one intermediate bead 50 strung on each of said aforesaid members between the center bead and the outward end of said member and terminal bead means each mounted at the end of an aforesaid member in alignment therewith for holding against longitudinal movement along said member an intermediate bead, said terminal means comprising 55 means engaging said member for securing the terminal means at the end thereof. 60

6. A cross-shaped ornament comprising a center bead having a pair of holes drilled therein on axes intersecting each other at right angles and lying in a common plane, a major tube member passing through one of said holes and extending from opposite sides of said center bead, a pair of minor tube members each having one end thereof disposed in said center bead proximate said first mentioned tube member and projecting respectively, from opposite sides of said center bead, and means for rigidly securing to said first mentioned member the ends of said other members disposed proximate thereto, in combination with at least one intermediate bead 65 strung on each of said aforesaid members between the center bead and the outward end of said member and terminal bead means each mounted at the end of an aforesaid member in alignment therewith for holding against longitudinal movement along said member an intermediate bead, said terminal means comprising 70 means engaging said member for securing the terminal means at the end thereof.
